UNITED STATES PATENT OFFICE.

WILLIAM M. THOMAS, OF CINCINNATI, OHIO, ASSIGNOR OF ONE-HALF TO
SAMUEL W. SKINNER, OF SAME PLACE.

ELECTRIC-ARC LAMP.

SPECIFICATION forming part of Letters Patent No. 278,293, dated May 22, 1883.

Application filed August 21, 1882. (No model.)

To all whom it may concern:

Be it known that I, WILLIAM M. THOMAS, of Cincinnati, Hamilton county, Ohio, have invented certain new and useful Improvements 5 in Electric-Arc Lamps, of which the following is a specification.

My invention relates to improvements (which fit them for use "in series") in those arc electric lamps whose arc-interval is automatically 10 regulated by the electro-magnetic action of a helix in circuit with the arc upon an armature that is mechanically connected with one of the electrodes.

My previous patents, No. 263,246 and No. 15 263,247, of 22d August, 1882, may be referred to for more specific description of features common to my several patents in this class.

It is well known that no two arc electric lamps employed in series behave precisely 20 alike. In one lamp the magnetic lift incident to increased current-flow takes place more promptly and with greater facility, with a consequently greater arc-interval, than in the others. Such disproportionate increase of arc- 25 interval in one lamp necessarily weakens the current throughout the series, and thus detracts from the lifting-power of all, but most so from those of the most sluggish movement. The heavier working-lamps, thus dwindling in 30 illuminative action, cease one by one to respond to the continually-waning magnetic energy. In strong contrast with and at the expense of this enfeebled action of the weaker lamps the arc of the most susceptible or easiest-working lamp continues to expand until it practically 35 monopolizes the effective activity of the entire circuit. Such unequal action is remedied by the provision of a high-resistance helix, shunting the arc through which current is diverted 40 in proportion to the relative resistance of said high-resistance helix and of the arc, the energy of said high-resistance helix always acting in opposition to that of the suction-core. The resistance of said high-resistance helix is so fixed 45 that when the arc is of normal length the forces centered on the electrode movement are in equilibrium. The two conditions of abnormal arc-length adjust themselves as follows: (a) When the arc-resistance is below normal, 50 so little current is diverted through the high-resistance helix that its energy is inappreciable and the suction-core action is unopposed

in its duty of lengthening the arc. (b) When the arc-resistance is above normal, the energy of the high-resistance helix is increased sufficiently to overcome that of the suction-core and to reduce the arc to its normal condition. When this adjustment has taken place, the lamp in question resumes its normal resistance. Each lamp adjusting itself in the manner described insures normal current-flow and equal illuminative action throughout the series. In devices heretofore employed or proposed for this purpose the activities of the electro-magnetic instrumentalities have, it is believed, 65 been restricted to the retractile or arc-opening motions, the still more important protractile or arc-closing actions of the electrodes being accomplished solely by gravity, the dynamic or electro-moving influences of the electro-magnet being for the time being non-existent and, so to speak, dead. In such devices it has been customary to employ armature members of considerable weight, which weight it has been part of the duty of the prime helix to overcome, requiring the powerful magnetic action 70 of many layers of wire, with a correspondingly high resistance and severe draft upon the current-supply. The device hereinafter described not being dependent for its action on gravity, 75 or employing only sufficient of it to insure electrode contact when the current is off, a prime helix of comparatively few layers and low resistance suffices, and any abnormal elongation of the arc is self-corrective by the restriction 80 of the shunt action, under all circumstances, to its proper functions of shortening the arc.

My invention, as to its leading features, is directed to means whereby the entire automatic adjustments or self-righting movements 90 are those of the electro-attractive elements themselves, gravity being either dispensed with, or, when used, acting in a subordinate or auxiliary capacity merely.

In devices of the kind heretofore employed 95 the automatic correction has depended on means whereby the theater of the inductive action of the high-resistance shunt-helix has been the armature itself, and has depended upon setting up in the armature polar tendencies the reverse of those induced by the prime, so as to neutralize or even for the moment reverse the same. In those forms of such shunts in which the differential wire is wound upon

the prime bobbin there is a serious objection to this so-called "differential method"—viz., its liability in those extreme fluctuations which it is most important to control to become subject to a false or reverse action, whose effect is not to narrow but to widen the separation of the electrodes, even to the extent of rupturing the arc and extinguishing the lamp. This in such arrangements is liable to occur whenever the shunted current acquires sufficient relative strength to give its helix an inductive potential exceeding that of the prime. In those forms of such shunts in which the differential wire is wound upon the armature, a serious loss of magnetic effect from the reduction of the armature substance, and loss of proximity to the prime excitant, to provide room for the wire, ensues.

In the preferred form of my present invention the inductions of the prime helix upon the armature (suction-core) are wholly unaffected by the shunt, and the corrections for series are wholly dependent on the attraction between the prime and the shunt. With this object in view the armature and shunt-helix are so attached to one another as to cause them to be attracted in opposite directions by the prime, with reverse effects upon the position of the electrode—at one instant retractile, at another protractile—according to the, for the time being, dominant attraction of core or shunt, respectively. In my preferred forms the armature, (whether ferro-magnetic or solenoid,) the shunt-helix, and the holder of the positive electrode constitute integrally attached parts of a single moving member, and the electrode, sharing in every motion of this member, takes part in all its perturbations, protractile as well as retractile.

In the preferred type of my present invention the prime helix, conveying the current to the arc, although, as heretofore, stationary during normal changes of the arc-interval, is capable of momentary disengagement and shift of position whenever the arc-interval becomes too great for rectification by the ordinary shunt action.

In the accompanying drawings, Figure 1 is a front elevation of the preferred type of my present invention. Fig. 2 is a side elevation, and Fig. 3 is an axial section, of the electrodynamic members. Fig. 4 is the front elevation of a lamp which embodies certain features of my invention. Figs. 5 and 6 are, respectively, side elevations of the prime helix and of the shunt-helix, with its integrally-attached armature, as employed in the form shown in Fig. 4.

In the preferred type of my invention, A, Fig. 1, may represent a slab, plate, or board, preferably of dry wood or other non-conducting material, for attachment and insulation of operative parts. The plate A carries on its upper side two binding-posts, P and N, for the respective attachment of the positive and the negative rheophores. In Fig. 1 the plate A is, by means of tube or cage B, shown con-

nected below with another non-conducting plate or collar, C, which carries a pendant, D D', that supports at its lower part a negative electrode, E, which may be of "carbon," as shown, or (when immobility of the point of light is desired) of refractory metal. The negative electrode has electrical connection, by arm D of pendant D D' and by cage B, with the negative rheophore N.

The preferred type of my invention has extending vertically through and immovably attached to plate A a brass rod, F, which, being coincident with the axis of the tube B, terminates at or about the level of the collar C. This rod, called the "pendant-rod" or "pendant-conductor," serves the twofold purpose of a conductor and a means of suspension of the electro-attractive mechanism. The upper end of the rod F has electrical connection p' with positive binding-post P.

Embracing the rod F is a hanger, G, which has hinged to its top a pawl or clutch, H, or other suitable fast and loose device, which is, by means of a weighted heel, h, or by a spring, held normally at such obliquity as causes it to nip, and, with its attachments, to remain suspended from the rod F. Attached to, but electrically insulated from hanger G, is a brass bobbin, I, of a helix, J, of insulated wire, which connects above, through hanger G, clutch H, and rod F, with positive rheophore, and below by brush K and other members, now to be described, with positive electrode L. The group of members G H I J K is stationary during the normal action of the lamp, but drops at distantly-recurring intervals, as hereinafter explained. This intermittently-dropping group of members is known in the present specification as the "element Y."

The positive electrode is confined in a brass holder, M, of tubular form, whose upper extremity is screwed within the lower extremity of a soft-iron cylinder, O, that constitutes the armature or suction-core, against which the brush K, before spoken of, impinges. The said suction-core occupies the interior of the prime helix bobbin I, and has screwed into its upper end the non-conducting bobbin Q of a high-resistance helix which shunts the arc, and is so wound as to be attracted by the prime helix in proportion to current-flow in said shunt-helix. The shunt-wire R connects at its receiving end by spiral S with hanger G, and at its discharging end by brush T with cage B, which cage connects with negative binding-post N. A sleeve, U, of vulcanite, serves to insulate from pendant-rod F the electrode-holder M and armature O. Attached to the upper end of shunt-bobbin Q is a yoke, V, that extends upward through orifices g in hanger G, and which unites at its top with tappet V', which in the lamp's normal condition is held (by the electro-dynamic force which acts on the suction-core) out of contact with the clutch H. The yoke V V', shunt-helix R Q, core O, electrode-holder M, and positive electrode L, will be seen to be parts of one shifter member,

which is held suspended at varying heights relative to the prime helix J, according to the predominance of the upward or downward attractive forces resident in the core and the shunt-helix, respectively. This single-shifting member, which will hereinafter be designated as the "element Z," is by these opposing forces held in such relation to the prime helix as that the centers of the perturbations of force of the 5 core and shunt-helix are respectively restricted to the upper and lower halves of the prime helix's field of energy. Except at distantly-recurring fluctuations, consequent on the separation of the larger masses of cinder ("tack-heads") from the negative electrode, or from the carbon-shortening effects of protracted lamp action, the member Y, including the prime helix, remains absolutely quiescent, and hence may be regarded as normally a fixture in 10 relation to the oscillating member Z, of which the electrode forms a part.

The parts are so adjusted that the closing of the circuit operates, through the attraction of the core, to separate the electrodes the proper 15 distance for a normal arc. A slight increase of arc-interval beyond the normal increases the current-flow in the shunt-helix, which is followed by an attracting downward of the shunt-helix, and a consequent dropping of the 20 electrode. On the contrary, a diminution of arc-interval, by diminishing the mutual attraction between the prime and shunt helices, lessens the force opposed to the core-suction, and sets the core free to again lift the electrode. Any excessive electrode-lift—such as 25 by establishing a very high resistance arc—would be prejudicial to the series current flow, possibly even to the extent of arc-rupture and extinguishing of series—is remedied by the 30 energy imparted to the shunt by the increased current-flow over it. This energy operates to depress the moving element Z and to shorten the arc of the lamp subject to such action. These perturbations, for the most part, proceed without entailing a sufficient fall of the 35 armature to disengage the clutch H; but when the arc-interval becomes excessive, as must occur in time by the gradual disintegration of the carbon, and sometimes occurs suddenly by 40 the casting off of a cinder, the shunt action prevails sufficiently to bring the head V' in contact with the clutch H, so as to momentarily disengage the same, and to permit the prime helix and all its appendages to drop, 45 with its clutch, again out of reach of the head or tappet V'. In falling the prime helix is arrested by clutch H before it gets out of its field of energy over the suction-core O. When the arc is too long the attraction between the 50 prime and shunt helices draws the member Z toward the member Y. Then, if the mechanism does not allow sufficient space for the high-resistance helix R to adjust the arc, the tappet V' pushes against the clutch H, and, 55 as soon as the push is strong enough to loosen the clutch, the entire mechanism begins to fall down the pendant-rod, with consequent

shortening of the arc; but this shortening of the arc by decreasing current-flow through the high-resistance helix withdraws the opposition of the latter to the energy of the suction-core, and the member Z is, so to speak, held suspended by the electro-dynamic attraction of the member Y on the suction-core, while said member Y is by force of gravity moving 60 downward. As soon as pressure is taken off clutch H by the motion incident to said attraction of the suction-core the clutch again takes hold of rod F, and the lamp has adapted itself to a shorter electrode. This action is so 65 instantaneous and so perfect that there is no visible variation in the light given off. Several consequences ensue from the impact of the tappet V' with the clutch H of great value and importance—for example, the preponderance of core-suction incident to the electro-dynamic inactivity of the helix R, and the momentary check which its contact with the element Y imparts to the oscillating element Z, coact to cushion the fall of the latter and prevent collision of the electrodes, while the almost instantaneous relief of the clutch H from the pressure of tappet V' permits prompt resumption of clutch action and of immobility of the element Y. The prime 70 helix, with its entire dependent system of electro-dynamic members, having assumed a new position on the pendant-rod, the normal automatic righting movements are resumed and continue until the carbons are again so shortened by combustion as to necessitate a repetition of the automatic drop of the prime helix, with its adjuncts, in the manner above stated. These actions and counteractions are so prompt and at the same time so delicate as to prevent 75 either actual impact or excessive separation of the carbons during lamp action.

An important feature common to the above-described typical form and my aforesaid contemporary applications is the absolute mechanical oneness and concurrent motion of core, shunt, and carbon with the consequent direct agency of the electro-magnetic forces in every carbon movement.

While possessing certain generic features in 80 common with the lamps described in several of my contemporaneous applications, the above-described typical form of my present invention is specifically distinguished in several important particulars—for example, the prime helix, 85 while, like said forms, stationary during normal action, is (in company with the entire regulating mechanism) made capable—on the occurrence of extreme carbon separation—of intermittent momentary drop, thus enabling the 90 use of carbons of much greater length than that of the prime helix bobbin by different specific means to those described in said forms.

Some of the above-stated characteristic features of my invention may be employed in various forms of electric lamps. For example, a prime helix may be employed which is absolutely stationary, as is shown in former patents of mine. The shunt and core may be so

attached as to have their potential centers both below that of the prime, the core acting by attraction toward and the shunt by repulsion from the prime; or the shunt may, as in Fig. 5 4, have such longitudinal distance from the core as to act by attraction, but in opposite direction to the core, and, as in this form, the armature may have fast and loose connection with the electrode. The core may consist of 10 a soft-iron armature or magnet, as shown, or of a solenoid. The frame which attaches the shunt-helix to the core may be provided with a rolling or sliding contact, X, with a bared track upon the prime helix's periphery, so as to 15 permit the gradual shifting of the prime helix's electro-dynamic field, and to permit the use of carbons of any desired length. Finally, the 20 arc-opening and arc-closing elements may be made to change places relative to the prime helix, and to both act by repulsion instead of attraction, the core in such case occupying the higher position, and the integrally-attached electrode being the more distant one.

Specific features (shown in Figs. 4, 5, and 6) 25 are reserved for the subjects of one or more separate applications for patent. Parts in said figures of like functions to those of the preceding forms are similarly designated. As hereinbefore intimated, this form is introduced 30 to further illustrate certain distinguishing characteristics of my invention—such, for example, as a high-resistance shunt attached integrally to and simultaneously shifting with the core such longitudinal distance as that 35 both act by opposing attractions toward the prime helix, without electrically affecting each other. In this modification the plate C', of vulcanite or other rigid non-conducting material, affords the means of attachment of the following parts, to wit: the positive and negative binding-posts N P of the pendant D D', which 40 supports the negative electrode E, and whose leg D constitutes part of the current-channel to the negative binding-post and the frame 45 B', from whose upper part depends the bobbin I', of brass or other diamagnetic material, grooved longitudinally at its upper part, as at i' i'', and reduced in diameter at its lower part, as at i''. Insulated wire from the positive 50 binding-post being conducted to the groove i', is carried down the same, and being wound spirally in two or more layers upon the part i'', so as to constitute the prime helix J, is conducted off along the groove i', and thence 55 to the brass holder M of the positive electrode L.

A frame, W, carries at its lower part a tube, O, of soft iron, which constitutes the suction-core, and at its upper part takes the form of 60 a bobbin, w, upon which is wound in any desired number of convolutions a wire, R, of higher resistance than the normal arc, and which connects the positive and negative binding-posts in such a manner as to shunt the arc. 65 As in the form shown in Figs. 1, 2, and 3, the core O and the shunt-helix R are held by frame W at such relative longitudinal distance as to

place the centers of their activities one always below and the other always above the field-center of the prime helix J, and out of 70 electrical influence with each other, and the shunt-helix R is so wound as when energized by the overflow-current to be attracted downward in opposition to the upward attraction of the core O.

The electrode-holder M has a stem, M', which, extending upward through the center and being insulated from the tubular members O I B', is in the normal condition of the parts upheld by hook 1 and clutch 2. Depression of 80 the frame W, by the predominating influence of the shunt R, operates to momentarily release the stem and permit the electrode to drop so as to shorten the arc.

The expressions "integral attachment" and 85 "rigid attachment" used in this specification are intended to mean that the parts referred to are inseparable during lamp action.

I am aware that it is not new to secure automatic adjustment of the carbons of electric- 90 arc lamps by a provision of two solenoids or electro-magnets, one of which has a coil of low resistance forming a part of the lamp-circuit, while the other has a coil of higher resistance forming a part of a by-pass or overflow-circuit, 95 such a device being described in the French patent to Lacassagne and Thiers, of 1855, and again in the device of Tochikoleff, issued in 1869, and described in the "Semiere Elec- 100 trique" of 1st of May, 1880, and again in English patent to Frederick von Hefner-Altenbeck, December 4, 1878, and in United States patent to the same, of June 21, 1881. I therefore disclaim novelty in such expedients, broadly considered.

Whatever novel subject-matter I have set forth and not claimed or attempted to claim herein, I have claimed or attempted to claim in other applications, or have reserved to be claimed in future original applications.

I claim as new and of my invention—

1. In an electric-arc lamp for series use, the combination, with a relatively-stationary helix in the arc-circuit, of an oscillating member composed of a duplex core interior to said helix, whose parts are integrally attached to each other and to the carbon-holder, and of which one part is a soft iron or equivalent core proper and the other a shunt-helix of high resistance, whereby the parts of said member respectively operate, the one to retract and the other to protract, said holder with each varying relation of the direct and the shunted currents, substantially as and for the purpose set forth.

2. In an electric-arc lamp for series use, whose arc-current traverses a relatively-stationary prime helix, an oscillating member of the following construction, to wit: a carbon-holder having integral attachment to a suction-core, which core is integrally attached to a high-resistance shunt-helix within the prime helix, and at such longitudinal distance from said core as to subject the said oscillating

member to independent oppositely-directed attractions and repulsions of said shunt and core, substantially as and for the purpose set forth.

3. In an electric-arc lamp for series use, the oscillating member consisting of the suction-core O, having integral attachment to carbon-holder M, and to the magnetically-independent high-resistance shunt R, interior to the relatively-stationary prime helix J in the arc-circuit, substantially as and for the purpose set forth.

4. In an electric-arc lamp for series use, having a relatively-fixed helix in the arc-circuit, the oscillating regulator fastened to the positive electrode, and consisting of the following members—all interior to and coaxial with said fixed helix—to wit, a suction-core of said helix and high-resistance shunt, having endwise attachment to said core, substantially as set forth.

5. In an electric-arc lamp for series use, the combination, with a relatively-fixed helix in the arc-circuit, of the longitudinally-shifting member comprising the described integrally-attached elements—all coaxial with and interior to said helix—to wit, the carbon-holder M and suction-core O, below the potential center of and attracted upward by said helix, and the endwise-attached high-resistance shunt R, above said helix's potential center, and whose convolutions and current-flow are such as to subject it to the downward attraction of said helix, in the manner and for the purposes set forth.

35 6. In an electric-arc lamp for series use, the combination, with the relatively-fixed prime helix J, of the described armature, arranged within said prime helix, and adapted to oscillate freely along said helix's geometric axis, and 40 whose two elements and the carbon-holder are attached endwise to one another, one element being a suction-core, or its described equivalent and the other a magnetically-distinct high-resistance shunt, which respectively operate to retract and protract the said holder as the arc and shunted currents respectively prevail, substantially as set forth.

7. In an electric-arc lamp for series use, having a relatively-fixed helix, J, in the arc-circuit, the oscillating member Z, interior to said helix, consisting of the described rigidly and endwise-

attached parts—to wit, upwardly-attracted suction-core O, downwardly-attracted high-resistance shunt R, and carbon-holder M, the described construction of said member being 55 such that the carbon-feed is wholly due to the concurrent movements of carbon-holder with said shunt, of which it constitutes a projection, as set forth.

8. In an electric-arc lamp for series use, the combination, with a prime helix in the arc-circuit, of the oscillating member Z, composed of the following rigidly-attached and concurrently-moving members, to wit: suction-core O, high-resistance shunt-helix R within said 65 prime helix, and the carbon-holder M, substantially as set forth.

9. In an electric-arc lamp for series use, the combination of pendant-conductor F, in communication above with the positive rheophore 70 and below with the arc, with the intermittently-dropping member Y, (consisting of hanger C, clutch H, bobbin I, helix J, in electrical communication with said rod, and the brush K in electrical communication with the carbon-holder,) said member Y being constructed, as 75 described, to exercise oppositely-directed attractions upon and being in the described combination with the electro-magnetically suspended oscillating member Z, (consisting of upwardly-attracted core O, to which are integrally attached the carbon-holder M and the magnetically-insulated high-resistance shunt R,) the whole being combined and adapted to operate substantially as set forth. 85

10. In an electric-arc lamp for series use, the described organism of bearing-plate A, pendant rod and conductor F, intermittently-dropping member Y, (consisting of prime helix J, in circuit of the arc, and having hanger C and clutch H,) in combination with the oscillating member Z, (consisting of the following integrally-attached and concurrently-shifting members, to wit: electrode-holder M, core O, shunt-helix R, and tappet V,) the whole being combined and adapted to operate as set forth. 95

In testimony of which invention I hereunto set my hand.

WILLIAM M. THOMAS.
